PROCESS FOR THE PRODUCTION OF SIL-
VERLESS PICTURE AND SOUND RECORDS
BY THE CHROMATE METHOD

Max Botho Hollaender, Berlin-Friedenau, Germany, assignor to Sifco A. G., Schaffhausen, Switzerland

No Drawing. Application November 22, 1937,
Serial No. 175,982. In Germany December 1,
1936

1 Claim. (Cl. 95—5)

The suitability of the chromate method for the production of duplicate negatives and dia-positives has been known for some time. As special advantage of this process, absence of grain and the straight line quality of the gradation have been praised. Thus David writes (photographical Praktikum, 6th edition, page 604):

"There thus arises"—that is, according to the pinatype process—"a picture shaded in the high lights, half tones and shadows in the same sense as on the original plate used for copying."

Now it was found, in contrast to such views, that this straight line quality of the gradation is only present when a considerable darkening of the high lights of the subject is accepted as well, whereby, of course, the brightness of the projected image suffers. The sound strength is also affected to a considerably greater extent, since it is dependent on the density of the sound track and, in the variable density process, also on the density of the inoperative part of the sound track (see Eggert-Schmidt "Einführung in die Tonphotographie," 1932, page 69). In order to be able to make good copies, it is therefore necessary to work, in contrast to the opinions previously held in the pinatype process, in the region of the toe of the density curve of the chromate-containing material.

This, however, cannot be done if as has previously happened, a normal copy ready for projection is taken as the subject; for the light records and especially the sound records of normal copies are likewise situated more or less in the region of the toe of the density curve of the material employed. In a copying process carried out according to the present invention, the gradations in the high lights would flatten out considerably, so that the images there would show a matt and chalky effect. The sound rec-

ord which, in the control mark process, extends still further than the image into the toe, would not only become considerably softer but also distorted, since as a result of the flattening of the density curve, the assumption of undistorted reproduction—that is, the straight line quality of the transparency curve—would no longer exist.

These difficulties can be avoided by making the copying subject considerably denser, so that also the blackness of the lighter parts of the image and of the sound records are removed further up into the straight line part of the density curve of the silver, and, in fact, for this purpose it will be necessary to go so far into the straight line curve as is necessary to obtain a straight line copy transparency curve of the copy to be projected, while making use of the toe of the chromated material. Thus, for instance, on the control marking corresponding to the inoperative position of the sound track, the subject may be given a blackening of 9.7 to 0.9.

I claim:

Process for the production of silverless pictures and sound copies according to the chromate method, consisting in producing an intermediate positive copy from a silver negative containing a picture and a sound record on a silver salt sensitized positive film, the silver positive film receiving such a density that the light parts of the picture as well as the sound record lie completely in the straight line of the gradation curve of the positive material and producing a final copy from the said intermediate positive copy on a silverless chromate film, the picture and sound record in said final chromate copy lying in the toe of the gradation curve.

MAX BOTHO HOLLAENDER.
